LÉON GAUMONT, OF PARIS, FRANCE, ASSIGNOR TO STÉ L. GAUMONT
ET CIE., OF PARIS, FRANCE.

MEANS FOR OPERATING SYNCHRONOUSLY PHONOGRAFS AND KINEMATOGRAPHS.

SPECIFICATION forming part of Letters Patent No. 752,394, dated February 16, 1904.

Application filed December 17, 1901. Serial No. 86,277. (No model.)

To all whom it may concern:

Be it known that I, LÉON GAUMONT, a citizen of the French Republic, residing in Paris, France, have invented certain new and useful Improvements in Means for Operating Synchronously Phonographs and Kinematographs, of which the following is specification.

This invention relates to a simple and electrical means for accomplishing the purpose set forth in the title and hereinafter explained.

In principle the velocity of the kinematograph, or rather the number of images transmitted per second, is not absolute, the human eye being capable of supporting variations of velocity without being shocked thereby, while the ear cannot support the least variation in the velocity of a phonograph, because such variations would cause not only a change in the depth of the sounds, but also a change in their ratio.

From what has been stated above it will readily be understood that the employment of motors, electric or other, for driving these appliances separately will not give good results if their synchronism is obtained by means of a speed regulator or governor upon each of them unless the phonographic cylinders employed have been recorded strictly at this velocity. Now unless these phonographs could be regulated once for all in such a manner that they should invariably operate exactly at the same velocity whatever might be the condition of the parts (including those of governor) as regards lubrication a cylinder recorded at Paris, for example, would not be correct for an apparatus sold in the provinces or abroad. Under these conditions it is essential that it should be possible to regulate the velocity of the phonograph so that it shall articulate correctly—or be in tune, so to speak—and that the kinematograph should instantly undergo these variations—that is to say, should be absolutely synchronous with the phonograph, whatever the velocity of this latter may be. I have therefore sought to construct mechanism requiring no regulation, and therefore incapable of getting out of order, and permitting this synchronism of the two appliances to be obtained, while at the

same time permitting the velocity of the kinematograph to be regulated. In order to effect this, I cause the phonograph or a part having a constant ratio with the phonograph to govern the velocity of the kinematograph by the means to be hereinafter described with reference to the accompanying drawings, wherein—

Figure 1 is a diagrammatic view of the motor for driving the kinematograph, the connector at the phonograph, the circuits, and the generators. Fig. 2 is a somewhat diagrammatic general view of the entire apparatus. Fig. 3 illustrates the adaptation of another form of motor for driving the kinematograph.

In Fig. 1, A designates a fixed Gramme ring forming the field-magnet of a motor and B the armature thereof in the nature of a Siemens H-coil. This is the motor for driving the kinematograph. I is a generator the poles of which are connected with the coils of the armature B.

A collector C, the number of the sections of which is equal to the number of sections in the Gramme ring A, (eight in this instance,) is arranged at any desired distance—say ten, twenty, or thirty meters—from the ring and each of its sections connected, as shown in Fig. 1, to one of the corresponding sections of the ring by means of eight wires insulated one from the other, but forming together a flexible cable. Providing the successive sections of the ring are connected to the successive sections of the collector the connection may be made in either direction, the only result being a change in the direction of rotation. Two brushes D and E are mounted upon a support adapted to oscillate around the center of the collector C, which is fixed. If these two brushes are connected, respectively, to the two poles of any convenient source of electricity J and if they are caused to rotate simultaneously in one direction or the other at any suitable velocity, I produce in the fixed ring A corresponding polarities, the law of displacement of which will be rigorously the same as that of the brushes D and E. Consequently if I send through the Siemens coil B a permanent

current this coil will exactly follow the movement of the brushes D and E. It is obvious that the Siemens coil may be replaced by a permanent magnet or even by an iron mass 5 only; but the dimensions being equal the power of the motor will be thereby diminished. In these conditions it is only necessary to connect the coil B to the kinematograph by means of gearing having a suitable ratio and to connect in the same manner the brush to the phonograph in order that the two appliances shall start at the same time and run with an absolutely synchronous velocity or what comes to the same thing with a suitable and perfectly 10 constant velocity ratio. In this case the motor A B should be more powerful than is necessary in order to merely rotate the kinematograph, because its velocity depends only upon the phonograph, and it should (if this latter 15 starts rapidly) have a couple sufficient to instantly overcome the inertia of the kinematograph. There is therefore no need to regulate the velocity of the motor by the employment of a rheostat, brake, or the like. The 20 driving-couple being sufficient with a predetermined voltage, it is only necessary to insert between the source of electricity and the motor A B a rheostat absorbing any excess of voltage. If, for example, the motor has 25 been constructed for producing the needful driving effort with twenty volts and ten amperes and if it is connected to a circuit of one hundred and ten volts, it will only be necessary to insert a rheostat absorbing ninety volts 30 ten amperes in order to insure absolutely synchronous operation of the two appliances. Besides as an excess of strength of the motor has 35 been provided the voltage at the terminals may undergo a small variation without inconvenience. 40

I would call special attention to the fact that the motor for the phonograph may be of any convenient kind, such as a spring, gravity, electric, or other motor, and that the sole condition which should be fulfilled by the phonograph is that it shall be connected by parts of constant ratio, such as gear-wheels or tangential screws, with the brush. The phonograph therefore retains all its means of regulation, and no perturbation can be communicated to it by the operation of the kinematograph. 45

I illustrate, by way of example, in Fig. 2 an arrangement of the two appliances as a 50 whole. Their mutual positions may, however, be varied according to requirements. A B is the motor previously described. A toothed clutch F enables the motor to rotate without driving the kinematograph. This clutch is 55 operated by means of the handle P. The toothed wheel G, which is loose upon the driving-spindle, is adapted to be driven by the clutch. It gears with the wheel H, fixed upon a spindle of the kinematograph K. A flexible 60 cable O, connecting the motor A B to the fixed

collector C, contains all the conductors connecting the various sections of this collector with those of the ring A of the motor. The brush-holders D E are fixed upon the shaft of a sprocket-wheel N, which gears by a chain 70 with the wheel M, forming part of the mechanism of the phonograph L. This wheel M imparts a movement of rotation to the pinion N, and consequently to the brushes D E. x indicates insulated metallic rings, respectively 75 in contact with two brushes d e. They are connected to the source of electricity J and conduct the current to the brushes D E.

It may be stated that the motor Z of the phonograph L drives the latter and also the wheel 80 M through a suitable train of gears, as in ordinary clock mechanism.

The operation is as follows: A signal of any suitable kind, such as the ringing of a bell or the sounding of a whistle, is arranged to 85 be given some seconds before the commencement of the piece or the like to be rendered by providing upon the cylinder an appropriate mark either before the record has been made or subsequent thereto, the piece being repeated 90 in this latter case for that purpose. This having been done and the apparatus being arranged as shown in Fig. 2, the phonograph is started. The kinematograph being thrown out of engagement, its motor A B at first runs 95 free, and at the exact moment at which the signal is given by the phonograph the kinematograph is thrown into gear by means of the handle P, and the two appliances run with absolute synchronism to the end of the piece. 100

It is only necessary when the phonograph film or roller is being recorded to form the mark upon the same which produces the signal in order that this engagement may be effected at the precise moment which will cause 105 the views shown to correspond with the sounds uttered.

In order to prevent any injury to the parts or stoppage of the motor A B at the moment at which engagement is effected, I interpose 110 between this motor and the clutch a spiral spring R, the torsional strength of which is such that in its position of repose it corresponds to the minimum of the couple necessary to maintain the kinematograph running. 115 At the moment of engagement this spiral spring receiving the movement suddenly will be wound up by several revolutions, and thus progressively increasing the driving-couple transmitted to the kinematograph will start this latter and enable it to attain its normal velocity. The variation thus introduced into the normal connection between motor and kinematograph is but momentary, and when once the kinematograph is running the spring 120 unwinds of itself, since its strength in the condition of rest is slightly greater than the normal driving-couple of the kinematograph, and synchronism will be established. The time occupied in effecting this is exceedingly short 125 130

and the variation so slight that it passes unnoticed.

It is not essential that the motor should be constructed in the manner described, and the 5. ring may rotate, the arrangement then being as follows:

Fig. 3 represents a Gaiffe motor the collector of which has been removed and upon which has been arranged between the armature and the bearing as many insulated rings 10 as there are sections. Each of these sections is connected to the corresponding ring and each wire of the cable proceeding from the fixed collector of the phonograph is connected 15 with a brush resting upon this ring. The result is the same as in the arrangement first described and the principle also remains the same.

Having thus described my invention, I 20 claim—

1. The combination with a phonograph and its motor, of a kinematograph, an electric motor which drives the latter, a source of electricity, and means controlled by the motor of 25 the phonograph for distributing the current supplied to the field-magnet of said electric motor in constant angular relation to the phonograph, whereby synchronous relations are maintained between the movements of the 30 phonograph and kinematograph.

2. The combination with a kinematograph, an electric motor for driving the latter, a pho-

nograph, a suitable motor for driving it, a collector having its segments connected successively with the respective sections of the field-magnet of said electric motor, a generator which supplies the armature of said electric motor, and means whereby the phonograph-motor drives the brushes of the collector as specified, of a generator having its terminals 40 coupled to the brushes of said collector.

3. The combination with a kinematograph, an electric motor for driving the latter, a phonograph, a suitable motor for driving it, a collector having its segments connected successively with the respective sections of the field-magnet of said electric motor, and a generator J having its terminals coupled to the respective brushes of said collector, of means whereby the phonograph-motor controls the supply 45 of current from said generator J to the field-magnet of the electric motor operating the kinematograph, whereby the latter motor is compelled to run synchronously with the motor of the phonograph, and means for uncoupling the kinematograph from its motor.

In witness whereof I have hereunto signed my name, this 6th day of December, 1901, in the presence of two subscribing witnesses.

LÉON GAUMONT.
